[57] CLAIM

The ornamental design for an automobile cruising skirt, as shown.

DESCRIPTION

FIG. 1 is a left side elevation view of the automobile cruising skirt;

FIG. 2 is a bottom plan view of the automobile cruising skirt;

FIG. 3 is a top plan view of the automobile cruising skirt;

FIG. 4 is a right side elevation view of the automobile cruising skirt;

FIG. 5 is a front elevation view of the automobile cruising skirt;

FIG. 6 is a rear elevation view of the automobile cruising skirt; and,

FIG. 7 is a left perspective view of the automobile skirt. The phantom lines showing the associated automobile are part of the environment of the invention and form no part of the claimed design.
